UNITED STATES PATENT OFFICE

2,400,449

BUNCH LOCATING MECHANISM FOR CIGAR MACHINES

Henry H. Wheeler, Bellerose, N. Y., assignor to International Cigar Machinery Company, a corporation of New Jersey

Original application October 8, 1938, Serial No. 234,001, now Patent No. 2,356,636, dated August 22, 1944. Divided and this application March 24, 1943, Serial No. 480,295

7 Claims. (Cl. 131—81)

This invention relates to cigar machines and constitutes a division of my co-pending application, Serial No. 234,001, filed October 8, 1938, which has issued as Patent No. 2,356,636 on August 22, 1944, for Bunch softening and shaping mechanism for cigar machines.

This invention relates primarily to improvements in bunch locating mechanism for use in positioning cigar bunches prior to their delivery into bunch shaping devices in order that each bunch to be shaped may be properly positioned and uniform bunches result because of the operation of the bunch locating mechanism.

It is, therefore, an object of my invention to provide an improved cigar bunch locating mechanism consisting of two positively operated cups which are adapted to be moved into and out of engagement with the ends of a bunch to be shaped.

It is a further object of my invention to provide a novel type of bunch locating mechanism which forms a part of a detachable bunch manipulating unit capable of being removed as a unit from the machine for replacement or repair.

It is a further object of my invention to provide a novel type of bunch locator in a cigar machine in which rotatable cups designed to engage the ends of a partially formed cigar bunch are mounted on a single support forming a part of a detachable bunch manipulating unit and so arranged that the cups can be moved to and from each other into and out of engagement with the ends of partially formed bunches.

It is a further object of my invention to provide a novel type of cigar bunch locator in which substantially all the parts necessary for locating and reciprocating the bunch locating cups are enclosed in order to prevent the access of dirt and other foreign material to the driving parts thereof.

It is a further object of my invention to provide a novel type cigar bunch locating mechanism for use in a cigar machine, which mechanism is provided with rotatable cups and means for adjusting the cups in order that they may be operative on substantially any length of cigar being formed in the cigar machine with which this type of bunch locator may be used.

With these and other objects not specifically mentioned in view, the invention consists in certain combinations and constructions which will be hereinafter fully described, and then set forth in the claims hereunto appended.

In the accompanying drawings which form a part of this specification, and wherein the several

reference characters designate the same or like elements:

Figure 1 is a sectional side elevation of the improved bunch locating mechanism;

Figure 2 is a sectional end elevation on line 2—2 of Figure 1;

Figure 3 is an end elevation of an improved cigar softening and shaping mechanism showing means for driving the bunch locating mechanism;

Figure 4 is a plan view taken on line 4—4 of Figure 1, showing means for adjusting the tuck end locator and its supporting bracket; and

Figure 5 is a view of the same mechanism taken on line 5—5 of Figure 1.

15 Referring to the drawings, the bunch locator mechanism of this invention is adapted to be used in cigar machines wherein each bunch is located prior to its transfer into the bunch shaping unit of a cigar machine. For purposes of 20 illustration, the bunch locating mechanism forms a part of a detachable bunch softening and shaping unit designated generally U (Figure 3) which is removably mounted on the machine table so that if for any reason it is desired to remove the 25 unit for repair or replacement merely by loosening screws (not shown) the unit can be removed as a whole and repaired or replaced.

Unit U is provided with a transfer 20 swinging on an oscillatory shaft 21 which transfers raw 30 bunches from the rolling table (not shown) to the cradle 24 enclosing the bunch softener drum 25 on shaft 26. A transfer 27 mounted on a swinging arm 28 on a shaft 29 picks up the bunch issuing from bunch softener drum 25 and cradle 24 and 35 delivers it to bunch locating position where it is substantially axially aligned with locating knurlers or cups 30a and 30b (Figure 1). Cups 30a and 30b then move inwardly and locate the bunch in transfer 27 for proper delivery to hollow jaws 31, 32 carried by arms 33, 34 hinged on a stud 35 in a cam operated lever 36 whereupon the 40 jaws 31, 32 are closed upon the bunch which is then further manipulated and moved by a plunger (not shown) into bunch shaping device (not shown).

The operating mechanisms of the transfer 20, bunch softener drum 25, cradle 24, transfer 27, bunch locators 30a and 30b, jaws 31, 32, and the plunger (not shown) which pushes a located 45 bunch into a bunch shaping pocket (not shown) are enclosed within a housing 43 whose bottom section 44 is detachably affixed to the base plate 45 of the cigar machine. For convenience in assembling the machine, the housing 43 is made up 50 of a central portion and two end portions. The

countershaft 53 is journaled in and protrudes from the bottom housing section 44 and carries on its protruding end a female coupling or clutch member 188 having a radial slot on its outer face adapted to admit a driving tooth of a male clutch member 189 fastened on one end of a stub shaft 190 carrying the bevel gear 52 at its other end, which is driven from a bevel gear (not shown) on a shaft (not shown), suitably driven from the main shaft of the cigar machine of which this mechanism forms a part. Thus the various operating mechanisms enclosed in the housing 43 are driven in a predetermined timed relationship to receive bunches from the rolling table and transmit them to successive pockets of the shaping turret (not shown), the position of the slot in the clutch member 188 being predetermined to obtain this relationship. When the bottom section 44 of the housing is detached from the base plate 45, the housing may be removed thereby withdrawing clutch member 188 from engagement with the clutch member 189. After the desired repairs have been effected, the housing may be replaced with its clutch member in coupled relation with the clutch member 189.

The shaft 21 is slidably mounted in bearings of frame 43 and carries a gear segment 69 and a drum cam 70. With segment 69 meshes a toothed segment 71 mounted on fulcrum shaft 72 and having a roller 73 in engagement with a cam track in one face of cam 57 on shaft 56 (Figure 3). The motion of arm 71, due to cam 57, causes the jaws of transfer 20 to enter slots in the upper end of the cradle 24 and the circumference of the softener drum 25 (Figure 3) and deposit the bunch between the cradle and the softener 25, during withdrawal of the transfer jaws.

The drum 70 engages with a roller 74 adjustably mounted in a slot extending circumferentially of the cam 70 in a portion of the housing concentric with the cam whereby the turning of the cam due to the motion of gear segment 71 causes an axial movement of shaft 21 for the purpose of bringing the bunch carried by transfer 20 into alignment with the softener drum 25. Cus-
tomarily, to insure firm bunch heads, the latter are preferably placed slightly out of center with the delivery end of the rolling table so that the bunches will be positioned from the head end. The amount of this axial movement may be regulated by adjustment of roller 74 along its slot, to compensate for the different positions at which the bunch will be delivered in the case of straight and curved rolling tables. Thus with a curved table the head end of the bunch delivered therefrom will be nearer to the head locator 30a than in the case of a straight rolling table. Therefore the bunch in being transferred from a curved table to the softener should be displaced axially sufficiently to bring its head into the proper position relative to the head locator, and the roller 74 should be adjusted to produce a greater axial displacement of the bunch during transference.

The cradle 24 has lugs 75 by which it is resiliently supported somewhat in the manner shown in Patent No. 1,765,831, granted to J. F. Halstead, June 24, 1930, from collar 76 mounted on bars 77 supported in housing 43 and has a resilient rod (not shown) fastened in collar 76 and fixed in the lug, the latter loosely fitting the bars 77. At its delivery end it carries a spring-tensioned finger (not shown). This finger is raised by the outgoing bunch and guides the bunch into the jaws of transfer 21 which have previously passed through slots (not shown) in the finger and assumed posi-

tions wherein the tips of the bottom jaws lie within the circumferential slots of the drum 25. The upper jaws thereof at this time are in a position to allow introduction of the bunch into the grippers of transfer 21 with their tips adjacent the finger. The shaft 29 carries a gear segment 79 meshing with a segment arm 80 mounted on fulcrum shaft 72 and provided with an arm 80a carrying a roller 81 in engagement with a cam track in a face of cam 58. The motion of cam lever 80 causes a transfer (not shown) operated by shaft 29 to carry the bunch from the softener discharge position for delivery position in jaws 31, 32 after dwelling in bunch locating position relative to locators 30a, 30b to permit accurate axial positioning of the bunch in the grippers of transfer 21 by the locators 30a and 30b, and then return to pick up the next bunch for delivery between locators 30a and 30b for locating.

The head end locator cup 30a (Figures 1 and 2) is fastened to a nipple 82 pinned to a shaft 83 journaled in a sleeve 84 slideable in bearings 85 of frame 43. The shaft 83 carries a pinion 86, and the sleeve 84 is provided with rack teeth 87. The tuck end locator cup 30b is revolvably mounted in a bracket 88 adjustably clamped on a sleeve 89 slideable in bearings 90 of frame 43, the sleeve 89 having rack teeth 91 and carrying a shaft 92 which has pinions 93 and 94 fastened to its ends. The pinion 94 through the intermediate gears 95 and 96 drives a gear 97 on the hub of the tuck end locator 30b, and the pinions 86 and 93 mesh with a gear 98 on a stud 99 in frame 43. The gear 98 is driven from a gear 100 on shaft 26 whereby the locators 30a and 30b are driven continuously in opposite directions. For accurate adjustment of bracket 88, the latter carries a pinion 161 meshing with rack teeth 162 cut into one side of sleeve 89, so that the turning of the pinion, after loosening the clamp screw 163, moves the bracket to the desired position.

A toothed segment arm 101 fulcrumed on a stud 102 in housing section 44 (Figure 3) and having a cam roller 103 in engagement with a drum cam 104 integral with gear 55 (Figure 3) engages with a gear 105 on a stud 106 (Figures 1 and 2) carried by a bracket 107 fastened to the interior of housing 43. A gear 108 meshes with the rack teeth 87 and 91 in sleeves 84 and 89. The gear 108 is turnably mounted on the hub of gear 105 and is angularly adjustable thereon upon unfastening screws 164 passing through arcuate slots 165 in gear 108 and clamping the latter against a shoulder on gear 105, to simultaneously move the locator cups toward or away from each other to compensate for various lengths of bunches. The motion of arm 101 thus causes simultaneous approaching movement of the knurlers 30a, 30b. The sleeve 89 has fastened thereon a guide arm 109 sliding on a stationary rod 110 in housing 43 and serving to prevent the sleeve from turning and thus to keep the locators 30a, 30b in alignment.

The invention above described may be varied in construction within the scope of the claims, for the particular device, selected to illustrate the invention, is but one of many possible concrete embodiments of the same. It is not, therefore, to be restricted to the precise details of the structure shown and described.

70 What is claimed is:

1. A cigar machine locator mechanism comprising a pair of parallel sleeves, shafts revolvably mounted within said sleeves, a pair of axially aligned bunch locators operatively connected to said shafts adapted to engage the head

and tuck ends of a bunch, means for continuously rotating said shafts in opposite directions to oppositely revolve said locators, and mechanism for moving said sleeves in opposite directions to bring the locators into engagement with the head and tuck ends of the bunch.

2. A cigar machine locator mechanism comprising a pair of parallel sleeves, shafts revolvably mounted within said sleeves, a pair of axially aligned bunch locators adapted to engage the head and tuck ends of a bunch and operatively connected to said shafts, means for continuously rotating said shafts in opposite directions to oppositely revolve said locators, and mechanism for moving said sleeves in opposite directions to bring the locators into engagement with the head and tuck ends of the bunch, the tuck end locator being supported by a bracket adjustably mounted on its respective sleeve to accommodate bunches of various lengths.

3. A cigar machine sub-assemblage comprising a housing, a countershaft journaled within said housing and protruding therefrom, the protruding end of said shaft being adapted to be connected to and driven from the main drive of a cigar machine, a pair of offset sleeves journaled within said housing and protruding therefrom, a pair of bunch locator drive shafts revolvably mounted in said sleeves and protruding therefrom, bunch locators operatively associated with said shafts, said locator shafts being driven from said countershaft, and said sleeves being each provided with rack teeth, and a pinion meshing with said rack teeth and intermittently driven from said countershaft.

4. In a cigar machine, the combination with a housing, of a pair of offset members supported within said housing and protruding therefrom, oppositely facing bunch locators mounted on the ends of said members in axial alignment with each other, mechanism for imparting axial movement to said members to move said locators axially into and out of engagement with the head and tuck ends only of a cigar bunch, said mechanism including rack teeth formed on each of said members and a pinion meshing with said rack teeth to produce opposite and equal axial movement of the locators toward or away from each other into and out of engagement with said

head and tuck ends of said cigar bunch upon rotation of said pinion.

5. In a cigar machine, a table, a housing, means detachably mounting said housing on said table, a pair of offset members supported within said housing and protruding therefrom, oppositely facing bunch locators mounted on the ends of said members in axial alignment with each other, mechanism for imparting axial movement to said members to move said locators axially into and out of engagement of the head and tuck ends only of a cigar bunch, said mechanism including rack teeth formed on each of said members and a pinion meshing with said rack teeth to produce opposite and equal axial movement of the locators toward or away from each other into and out of engagement with said head and tuck ends of said cigar bunch upon rotation of said pinion.

6. In a cigar machine, the combination with a housing, of a pair of offset members supported within said housing and protruding therefrom, oppositely facing bunch locators mounted on the ends of said members in alignment with each other, to engage the head and tuck ends of a cigar bunch, the adjacent faces of said members being provided with rack teeth, a pinion meshing with said rack teeth to produce opposite and equal movement of the locators toward or away from each other upon rotation of said pinion, and mechanism for intermittently rotating said pinion, said mechanism being adjustable to compensate for various lengths of cigar bunches.

7. In a cigar machine, the combination with a housing, of a pair of members offset from each other in a vertical direction and extending horizontally from said housing, one of said members extending a greater distance from said housing than the other, spaced bunch locators mounted one on each of said members in alignment and facing each other to engage the head and tuck ends of a cigar bunch between them, and actuating means within the housing acting on said members to impart equal and opposite horizontal movement toward and away from each other of said locators to bring the same together on the head and tuck ends of the bunch to locate the same.

HENRY H. WHEELER.
